UNITED STATES PATENT OFFICE.

HARRY JACOBS AND HANNAH JACOBS, OF NEW YORK, N. Y.

HAIR WAVING AND DRYING ATTACHMENT.

1,369,973.

Specification of Letters Patent.

Patented Mar. 1, 1921.

Application filed December 26, 1919. Serial No. 347,422.

To all whom it may concern:

Be it known that we, HARRY JACOBS and HANNAH JACOBS, citizens of the United States, and residents of New York, in the 5 county of Kings and State of New York, have invented certain new and useful Improvements in Hair Waving and Drying Attachments, of which the following is a specification.

10 This invention relates to improvements in a hair waving and drying apparatus which employs a hot air blast as the drying medium.

The object of this invention is to provide 15 an attachment which may be readily connected to any suitable hot air driving means.

A further object is to provide a device 20 of the character described which is readily operable by hand without the use of special supporting members.

The objects are attained by means of the device illustrated in the accompanying drawing, in which—

25 Figure 1 is a side elevation of the apparatus showing its application in use, and

Fig. 2 is a plan view of the attachment.

Referring in detail to parts, 1 designates 30 an air distributing duct provided with a pivotally connected attaching means 2. The said duct is provided with outlets 3 to which the drying units 14 are connected.

The attaching means 2 may be connected to any suitable air heating and driving device 44 which comprises the usual motor, 35 fan and casing and heating element and may be provided with a suitable handle.

The outlets upon the air distributer may vary in number and it is intended not to limit the number of same. 40

Various modifications may be embodied in this apparatus. It is therefore intended not to limit this invention to the particular construction shown.

Having thus described the invention, it is 45 claimed:

1. In a hair waving and drying apparatus, an attachment comprising hot air distributing means, pivotal connecting means for attachment to the source of hot air supply 50 and a hand holding means attached to the casing.

2. In a hair waving and drying apparatus, a hot air distributing means, pivotal connecting means attached thereto, suitable 55 means connected to the distributer to force hot air therethrough and a hand holding means attached to the casing.

Signed at New York in the county of 60 Kings and State of N. Y., this 20th day of December A. D. 1919.

HARRY JACOBS.
HANNAH JACOBS.
